UNITED STATES PATENT OFFICE.

JOHN WILLIAM PETERSEN, OF DAVENPORT, IOWA.

POLE-DROP.

1,355,568.

Specification of Letters Patent. Patented Oct. 12, 1920.

Application filed November 25, 1919. Serial No. 340,441.

To all whom it may concern:

Be it known that I, JOHN WILLIAM PETERSEN, a citizen of the United States, and a resident of Davenport, in the county 5 of Scott and State of Iowa, have invented certain new and useful Improvements in Pole-Props, of which the following is a specification.

My invention is an improvement in pole 10 props, and has for its object to provide a device of the character specified, especially designed for supporting the pole of a carriage in horizontal position, without any strain on the carriage when the pole is not 15 in use, the said prop being pivoted to the pole to swing into or out of operative position.

In the drawings:—

Figure 1 is a side view of a portion of a 20 pole having the improved prop in operative position,

Fig. 2 is a front view,

Fig. 3 is a side view of the neck yoke check,

Fig. 4 is a side view of one end of the yoke,

Fig. 5 is a plan view of the bolt for connecting the yoke to the pole.

Fig. 6 is a perspective view of the outer 30 end of the pole.

In the present embodiment of the invention, the pole 1 has connected therewith the yoke 2, the said yoke being provided at its center with a depending substantially U-shaped member 3, whose arms extend on opposite sides of the pole, and are pivotally connected thereto by the bolt 4 shown in Fig. 5. This bolt has a fixed head 5 at one end, and a detachable head 6 at the other

end, the said head being held in place on the 40 bolt by a pin 7 which passes through registering openings in the head and in the bolt.

The prop is composed of two strips or bars 8 of suitable length, which are pivoted on the bolt 4, which pivotally connects 45 the arms of the yoke 3 to the bolt, in such manner that the said bars or strips 8 may occupy the full line position of Fig. 1, or may be swung into the dotted line position of the said figure. When they are in the 50 full line position, it will be evident that the free end of the pole will be supported out of contact with the ground, while when the prop is in the dotted line position of Fig. 1 it will be out of the way where it will not 55 interfere with the use of the carriage.

A check 9 is connected with the pole for engagement by the yoke to limit rearward swinging movement thereof. This check has a depending pin 10 which passes through 60 an opening in the pole and is engaged by a nut 11 below the pole.

I claim:—

In combination with the pole of the carriage, of a yoke having intermediate its 65 ends a depending substantially U-shaped member consisting of a body rigid with the yoke and arms engaging opposite sides of the pole and pivotally connected thereto, a prop mounted on the pivotal connection 70 of the yoke arms at each side of the pole, and a stop for the yoke secured to the pole in rear of the yoke, said stop being mounted to engage the yoke when it swings rearwardly to prevent the engagement of the 75 yoke with the pole.

JOHN WILLIAM PETERSEN.
